UNITED STATES PATENT OFFICE.

GEORGE F. WOLFF, OF CHICAGO, ILLINOIS, ASSIGNOR TO SAGER METAL WEATHER STRIP CO., OF CHICAGO, ILLINOIS, A CORPORATION OF ILLINOIS.

METAL WEATHER STRIP.

Application filed March 5, 1923. Serial No. 622,713.

This invention relates in general to metal weather stripping, and has more particular reference to metal weather stripping provided upon the sash and parting strips of the window.

A principal object of the present invention is the provision of a weather strip of greater and more prolonged efficiency than those heretofore in use and which may be cheaply manufactured and readily installed.

One of the objects of my invention resides in providing an improved construction over that shown in patent to Charles A. Shogren, No. 1,195,108, of August 15, 1916, which patent discloses a complete weather strip including a parting bead which may be substituted bodily for the usual parting bead found in wooden window frames, and which parting bead includes a weather stripping portion adapted to co-operate with a complementary strip or strips fastened to the window sash whereby the space between the sash and the parting strip is effectively sealed.

One of the objects of my improved construction over that shown in the afore-mentioned patent resides in providing an arrangement for more easily attaching the weather strip to the face of this parting strip, and for also removably fastening the parting strip with its weather strip into the usual channel of the window casing or frame whereby it can be quickly removed for repair or assemble of my improved strip to the window sash.

Still a further object of my improved invention resides in my improved parting strip having recessed shoulders on that portion which projects from the window casing, a novel arrangement of sheet metal weather stripping attached to the front face of the stripping and extending over and around the sides of the parting strip to provide lateral flanges arranged in spaced apart arrangement from the outer walls of said shoddered recess so as to receive in such spaced portions, complementary angle strips fastened to the window sashes.

Yet another object of my invention resides in providing such complementary angle strips attached to the window sashes with outer hemmed or folded edges which lie

within the flanged portions of the strip attached to the parting strip, which hemmed edges not only provide tight contact with the lateral flanges but also eliminate any scraping action.

A further object of my invention is the provision of a weather stripping of this character, which, while requiring a minimum amount of metal, will possess improved protection against circulation of air through the window.

Numerous other objects and advantages of the invention will be apparent as it is better understood from the following description, which, taken in connection with the accompanying drawing, discloses a preferred embodiment thereof.

Referring to the drawings,

Figure 1 is a partial perspective showing weather stripping embodying my present invention installed in place; and

Fig. 2 is a horizontal section on an enlarged scale through the same.

For the purpose of illustrating my invention I have shown on the drawing a portion of a window casing or frame, indicated generally by reference character 11 and particular description of which is unnecessary to an understanding of my present invention. It should, however, perhaps be stated that this casing is provided with the usual parting strip receiving channels or recesses 12 and, in the present instance, rails 13 provide for the sliding of two window sashes 14.

My improved weather strip comprises a combined parting strip and sheet metal stripping attached thereto and adapted to co-operate with complementary sheet metal stripping attached to the window sashes. As clearly shown in Figure 2, the parting strip 15, which is adapted to replace the original parting strip in the window, has its sides cut away slightly throughout its length and from the casing or frame proper outwardly to provide recessed shoulders. The outer face of the parting strip is recessed, and in the present disclosed form of my invention, this recess consists of a channel or groove 17.

The weather stripping proper in the present preferred form of the invention,

comprises a metal strip seated in the recess or groove and having parts extending in the form of flanges along the sides of the parting strip in co-operative overlapped relation with angle strips secured to the edges of the sash and extending between the flanges mentioned and the parting strip itself. Reference character 18 indicates a central strip depressed throughout its length at 19 to extend into the channel 17, the portions of the strip adjacent said channel engaging or resting against the outer face of the parting strip. The metal of this central strip extends out beyond the side faces of the parting strip and is bent inwardly to form two flanges 21. Fastening means are provided within the groove or channel 17 and these means in the present instance consist of nails or brads 22 which are driven home through the portion of the weather strip arranged in the channel or groove 17, entering into the wood thereof with the heads engaging the material of the strip adjacent the outer edge of the recess and with the points cleated or clinched behind the strip.

Co-operating weather strips of angle form are indicated by reference character 25. One leg of this angle is secured against the side edge or face of the sash by screws 26 or otherwise, with the other leg of the angle arranged toward the parting strip. The free edge of this leg is reinforced, a convenient form of reinforcement being to fold the material back upon itself as indicated at 27.

Thus constructed both co-operating members of each pair of flange parts arranged between the sash and parting strip are reinforced, the flange part associated with the window sash by the return fold 27 and the flange part associated with the parting strip by close firm contact with its outer face.

The hemmed or folded edge 27 of each angle strip 25, in addition to having the function of forming a tight fit with the lateral flanges 21 of the strip attached to the parting strip, also provides a means for limiting the outward movement of the angle strips attached to the sashes. Experience has shown that when an installation has been in use a considerable time, there is a pronounced shrinkage of the sashes in the window frames. In other words, referring to Fig. 2, the sashes 14 shrink away from the frame 11, thus moving outwardly from this frame in a direction toward the bottom of the drawing as shown in Fig. 2. This shrinking movement will be limited by the hemmed edges 27 of the angle strips abutting the folded flanges 21, and since these edges are hemmed there will be no scraping action as there would be if the edges were raw.

It will be noted that the metal stripping

attached to the parting strip by the manufacturer lies close against the outer face of the parting strip with the flanges extending along its side and with the two parts firmly secured together in interlocked relation. The arrangement just described insures against deformation of the flange parts and the separation of the metal strip from the wood.

The parting strip is preferably secured in place by screws 28, which screws are shown in dotted lines in Figures 1 and 2 of the specification, taking through the metal stripping 18, the recess or groove 17 and on through the parting strip into the casing, the head 29 of the screw engaging the metal strip 18 opposite the presented faces of the parting strip along side the groove. These faces may be formed or shaped, if desired, on a slight rounded bevel to more closely follow the configuration of the strip 18 and relieve any necessity for providing sharp folds.

It will be noted from Figures 1 and 2 of the drawings that the sheet metal stripping 18 is fastened to the parting strip 15 by a spaced series of nails or brads 19 which pass through the re-entrant fold of the stripping 18 as it lies in the channel or recess 17, and thence into the parting strip 15. These nails or brads 22 are arranged in spaced relation longitudinal of the strip. In addition, in intervening spaced relation longitudinal of the strip, the screws 28 are fastened through the re-entrant fold of strip 18 as it lies in the channel or groove 17 of the parting strip, thence through the parting strip and into the frame 11 thereby detachably fastening my combined unit weather stripping in place.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A sheet metal weather stripping adapted to be attached to the parting strip of a window frame, comprising, in combination a parting strip having a front face provided with an intermediate thereof a recess extending longitudinally of the strip, a metal strip member extending longitudinally of the strip and having an in-fold lying in the center recess of the front of the strip with the metal adjacent the in-fold contacting with and bent over the adjacent faces of the front of the strip and over the sides thereof, so as to substantially overlie the recessed shoulders and spaced therefrom, and a second pair of strip members, each having an edge flange attached to an adjacent sash

- member, and each having a side flange adapted to underlie and contact with the lateral flanges of the first mentioned metal strip member.
5. 2. A sheet metal weather stripping adapted to be attached to the parting strip of a window frame, comprising, in combination with the parting strip having a front face recess longitudinally thereof at a point substantially intermediate the front face, a metal strip member extending longitudinally of said parting strip and having an in-fold of substantial width lying in and fastened within the front face of the parting strip with the adjacent portions of the strip extending across and lying in contact with the front face of said parting strip and thence laterally substantially parallel with the sides of the strip, a plurality of fastening means passing through the depressed portion of the in-fold of the strip and through the parting strip to hold said metal strip in position and separate strip members, each secured to a sash member and having a resilient flange overlapping and contacting with the lateral flanges of said first mentioned strip.
3. A sheet metal weather stripping adapted to be attached to a parting strip of a window frame, comprising, in combination with a parting strip having a central longitudinal recess on its front face and provided with recessed sides to form cut-out shoulders on the sides of said parting strip, a metal strip having a central in-fold positioned in the recess of the front face of said parting strip with the metal adjacent and on each side of the in-fold bent over so that when said strip is applied to the parting strip, said bent-over portions of the metal will lie in contact with the front face of the strip and will overlie the lateral recessed faces of the sides of the parting strip to provide flexible flanges and a pair of separate strips, each having a portion attached to a shoulder and having a portion forming a lateral resilient flange adapted to underlie the lateral flanges of the first strip and to make contact therewith.
4. A sheet metal weather stripping adapted to be attached to a parting strip of a window frame, comprising, in combination with a parting strip having a central longitudinal recess on its front face and provided with recessed sides to form cut-out shoulders on the sides of said parting strip, a metal strip having a central in-fold positioned in the recess of the front face of said parting strip with the metal adjacent and on each side of the in-fold bent over so that when said strip is applied to the parting strip, said bent-over portions of the metal will lie in contact with the front face of the strip and will overlie the lateral recessed faces of the sides of the parting strip to provide flexible flanges and a pair of separate strips,
- each having a portion attached to a shoulder and having a portion forming a lateral resilient flange adapted to underlie the lateral flanges of the first strip and to make contact therewith, the free ends of each of said separate strips being hemmed to provide portions of greater width, whereby not only to form a more effective seal but also to prevent the scoring of the under side portions of said first mentioned strip.
5. A parting strip comprising a body portion arranged to fit within the usual window sash groove, and having a recess in its outer face, a sheet metal strip having an intermediate disposed fold seated in said recess and so having its free edges bent over the outer face of said body, and extending substantially parallel with the sides thereof to provide lateral flanges and detachable means passing through said folded portion of the sheet metal strip into said parting strip and into said window sash whereby detachably to hold the same in assembled position.
6. A parting strip comprising a body portion arranged to detachably fit within the usual window sash groove, a sheet metal strip forming a facing for the front of said parting strip and bent over the sides thereof to provide lateral extending flanges for said parting strip and a detachable fastening means passing through the face of said sheet metal strip through said parting strip and into the window frame whereby said parting strip with its sheet metal strip may be quickly removed from the window frame.
7. In combination with a window frame, a parting strip therefor having a central longitudinal channel and having its lateral walls cut away to form recessed shoulders, sashes disposed on each side of said parting strip, a sheet metal strip having a folded portion seated in the channel formed in the front face of said parting strip and having its edges folded over in contact with the front edges of said parting strip thence along and substantially parallel to the cut away walls of said parting strip and in spaced relation therefrom fastening means passing through said folded portion of said sheet metal strip and into said parting strip, an L shaped sheet metal strip fastened to each sash and having one flange thereof lying within each lateral flange of the first-mentioned strip and making tight contact therewith.
8. A parting strip, comprising a body portion arranged to fit within the usual window groove sash and having a longitudinal recess in its front face and lateral cut-outs, a metal strip substantially U-shaped in cross-section with the bottom of the U-portion formed with an in-fold projecting in the direction of the legs of the U, whereby when said strip is positioned on the parting strip with the in-fold in the recess thereof

and fastening devices are passed through the in-fold into the recess and into the parting strip, the portions of the strip adjacent the in-fold will be drawn tightly against the front faces of the strip adjacent its longitudinal recess, so as to provide more effective resilient lateral flanges, which lie in spaced relation to the sides of the parting strip, two sash members, each lying on opposite sides of the parting strip and each having an independent strip provided with a portion attached to the sash and provided with a resilient flange member underlying the resilient flange of the first mentioned strip.

GEORGE F. WOLFF.
